UNITED STATES PATENT OFFICE

WILLIAM H. WINSLOW, OF CHICAGO, ILLINOIS, ASSIGNOR TO GEORGE W. DULANY, JR.,
OF CHICAGO, ILLINOIS

STEAM BOILER

Application filed February 14, 1927. Serial No. 168,016.

This invention relates to high pressure steam boilers particularly useful for railway steam engines, steam rail cars, buses, tractors, motor launches and the like, and is of the type that is made up of a number of sectional units which are a substantial duplicate of one another and which are readily removable for replacement purposes.

The main objects of this invention are to provide an improved form of high pressure boiler which will be exceptionally free from strains and stresses due to expansion of the generating tubes and connecting manifolds; to provide a boiler which will have high efficiency and excellent circulation; and to provide a boiler of this class which is made up of a number of standardized units or sections which are interchangeable and readily assembled.

An illustrative embodiment of this invention is shown in the accompanying drawings, in which,—

Fig. 1 is a vertical, sectional elevation of the improved type of boiler;

Fig. 2 is an enlarged fragmentary section taken on the line 2—2 of Fig. 1;

Fig. 3 is an enlarged fragmentary section taken on the line 3—3 of Fig. 1;

Fig. 4 is an enlarged fragmentary detail, showing the generating tube ribs which hold the tubes in spaced relation;

Fig. 5 is an enlarged fragmentary section of several generating tubes, showing their relative positions when assembled.

In its general arrangement and also in the details of construction, this boiler is designed to permit without injury the normal expansions and contractions due to the temperatures and temperature changes with which it must contend, and also when used as a locomotive boiler to withstand the mechanical shocks or vibrations imparted thereto.

The surrounding housing of the boiler is provided with an unobstructed floor covered with a heat resisting material for reflecting radiant heat upwardly into the boiler tubes. These tubes are arranged in two sets of overlapping and vertically disposed loops.

The lower ends of the tubes communicate with staggered manifolds extending verti-

cally along the side walls of the furnace and communicating with the upper ends of the tubes through separator elements of greater carrying capacity than the tubes. The function of these separator elements is to allow water to drain back into the vertical manifolds with a minimum disturbance of the upwardly rising steam. The steam is collected in substantially dry state by steam headers arranged at the upper end of the furnace and communicating with superheaters which are disposed in horizontally extending groups of conduits in spaces conveniently provided by the aforesaid two sets of looped tubes.

In the construction shown in the drawings the boiler comprises a suitable housing 1 which is provided with a smoke stack outlet opening 2 at the top thereof for carrying away products of combustion, and with suitable burners 3 and 4, located adjacent the bottom of the housing 1, for supplying fuel to the boiler. The floor of the housing 1 is constructed of the usual radiating heat material 5, as is customary in this type of boiler construction.

Enclosed within the housing 1, along two opposite sides thereof, are series of generating units, each of which comprises a vertically disposed, tubular, downcomer manifold 10, which is provided with a plurality of generating tubes 11 which communicate with the downcomer adjacent the lower portion thereof and disposed at an angle thereto. The generating tubes 11 are positioned on the downcomer, one above another, and lead outwardly and upwardly toward the opposite side of the boiler where the second series of units are positioned, the upper ends of the generating tubes being bent back upon themselves toward the downcomer 10 and terminating in spaced relation thereto.

The upper ends of the generating tubes 11 are attached to, and communicate with, a vertically disposed tubular, intermediate, separating upcomer manifold 15 which is supported by a strut circulating generating tube 16 which is mounted on, and communicates with the downcomer manifold 10. The manifold 15 acts as a separator for the steam

and water and is of greater cross sectional area than the combined cross sectional areas of the generating tubes 11 which communicate therewith, and of less cross sectional area than the combined cross sectional areas of a series of separating tubes 17 which provide communication between the manifold 15 and the upper portion of the downcomer manifold 10. A suitable insulating wall 18 is provided for shielding the separating tubes from direct heat and extends from the lower end of the manifold 15 along the supporting strut 16 on the rear side thereof to the downcomer 10.

15 The lower portions of the generating tubes 11 are offset or staggered with relation to one another, as shown particularly in Fig. 3 of the drawings, so as to present as great a number as possible of the tubes to the direct heat from the burners and the radiating surface 5 of the boiler, the points of bending of the tubes being in a vertical plane, as shown at 19, extending down to a point closely adjacent to the lower portion of the downcomer 25 manifold 10 in order that the units may be assembled by raising in a vertical direction for replacement purposes.

The boiler sections or units are mounted in staggered relation to one another so as to secure compactness on a mud drum 20 which extends along one side of the boiler, and the second series which extend along the opposite side of the boiler are mounted in the same manner and the two mud drums are connected 35 together as shown at 21 for equalizing purposes. A fire wall 22 surrounds and protects the mud drums and the connection fittings on the lower end of the downcomers from direct heat from the burners of the boiler. The 40 units comprising each series are assembled with their generating pipes, and in spaced parallel relation to one another, and the two series are so positioned that the generating pipes extend toward, and overlap, the generating tubes of the opposite series, the tubes 45 of one series alternating with the tubes of the opposite series and the adjacent sides of the generating tubes at the point of overlapping are each provided with ribs 25 placed diametrically opposite each other for holding 50 the tubes in spaced relation, these ribs being of such thickness as to entirely fill the normal spaces between the tubes when the boiler sections are assembled and closely abut against 55 each other in such manner that a suitable tie-rod (not shown) can be used to clamp the entire assembly of tubes snugly together. These separating ribs 25 also provide a baffle for the products of combustion in the fire box 60 of the boiler which is located substantially midway between the burner flames and the smoke stack 2.

The upper ends of all the manifolds of each series of boiler sections are connected 65 by suitable pipes and fittings 30 to a common

transverse steam header 31 and the headers 31 are each connected to a bank of superheating coils 32 which are enclosed in the space surrounded by the generating tubes, separating tubes and manifolds. In this manner the 70 baffles formed by the ribs on the adjacent sides of the generating tubes tend to deflect the gases and products of combustion outwardly against these banks of superheating tubes in a very efficient manner.

A bank of preheating coils 35 which may be used for either air or water, is placed above the generating tubes in such manner as to receive heat from the products of combustion just before leaving the boiler.

75 The water is supplied to the boiler by any suitable means (not shown) through pipes 40 which are placed concentrically in the mud drums 20, these pipes being provided with a series of short nipples 41, one nipple being 80 provided for each downcomer manifold, and extending upwardly adjacent the lower end thereof so that water is supplied in equal quantity to each of the boiler sections. The nipples 41 are of sufficiently small diameter, 85 relative to the connections used for mounting the downcomer manifolds, that water from the manifolds can pass around the outer sides thereof into the mud drum, and equalization 90 between the sections is thus secured.

95 In the operation of the boiler it is filled through the pipes 40 and the mud drums 20 and fuel is supplied through the burners 3 and 4. When the generating tubes 11 become heated and steam generated therein the 100 water and steam travel upwardly in tubes into the intermediate manifolds 15 wherein a partial separation of the steam and water takes place. Steam passes through the upper separating tubes 17 to the upper portion of the downcomer manifold 10 and the water returns through the lower separating tubes 105 of the series.

110 The relative cross-sectional areas of the separating tubes 17, separator manifold 15, and generator tubes 11 communicating therewith is so proportioned that a free and efficient circulation is maintained at all times without a reversal of circulation taking place 115 therein. The steam passes out through the connections 30 on the tops of the downcomer manifolds 10, thence into the steam headers 31. From there the steam travels to the superheating tubes 32 and thence to the engine or other appliance to which it is desired to supply steam.

120 The separating or spacing ribs 25 which are on adjacent sides of the overlapping portions of the generating tubes 11 take up the 125 rubbing or chafing action of the tubes due to vibration and relative shifting of the tubes and prevent the adjacent side walls from becoming rubbed thin and thus weakened. Ordinarily, in a boiler of this kind, 130 regardless of the precision and accuracy with

which the units are constructed and assembled in the boiler, it is impossible to maintain a definite space or clearance between the tubes on account of their warping and twisting due to the intense heat to which they are subjected. The ribs minimize such distortion of the tubes.

Although but one specific embodiment of this invention has been herein shown and described, it will be understood that numerous modifications may be made without departing from the spirit of this invention, as defined by the following claims.

I claim:

1. A boiler construction of the class described comprising an upright tubular downcomer manifold, generating tubes communicating with said manifold adjacent the lower portion thereof and inclined at an angle thereto, the upper ends of said tubes being bent back upon themselves towards said manifold, and intermediate vertically disposed tubular separating manifold communicating with the upper ends of said generating tubes, and means providing communication for water and steam from said separating manifold to the upper portion of said downcomer manifold.

2. A boiler of the class described comprising an upright tubular downcomer manifold, generating tubes having their lower ends communicating with said manifold adjacent the lower portion thereof, said tubes being inclined at an angle to said manifold, the upper ends of said tubes being bent back upon themselves towards said manifold, an upright tubular intermediate separating manifold communicating with the upper ends of said tubes, and a series of separating tubes providing communication between said separating manifold and the upper portion of said downcomer manifold.

3. A boiler of the class described comprising an upright tubular downcomer manifold, generating tubes having their lower ends communicating with said manifold adjacent the lower portion thereof, said tubes being inclined at an angle to said manifold, the upper ends of said tubes being bent back upon themselves towards said manifold, an upright tubular intermediate separating manifold communicating with the upper ends of said tubes, a series of separating tubes providing communication between said separating manifold and the upper portion of said downcomer manifold and means on said downcomer for supporting said separating manifold.

4. A boiler of the class described comprising an upright tubular downcomer manifold, generating tubes having their lower ends communicating with said manifold adjacent the lower portion thereof, said tubes being inclined at an angle to said manifold, the upper ends of said tubes being bent back upon them-

selves towards said manifold, an upright tubular intermediate separating manifold communicating with the upper ends of said tubes, a series of separating tubes providing communication between said separating manifold and the upper portion of said downcomer manifold, and a strut generating tube mounted on and communicating with said downcomer manifold for supporting said separating manifold.

5. A boiler of the class described comprising an upright tubular downcomer manifold, generating tubes having their lower ends communicating with said manifold adjacent the lower portion thereof, said tubes being inclined at an angle to said manifold, the upper ends of said tubes being bent back upon themselves towards said manifold, an upright tubular intermediate separating manifold communicating with the upper ends of said tubes, a series of separating tubes providing communication between said separating manifold and the upper portion of said downcomer manifold, and a heat insulating wall extending from said separating manifold to said downcomer manifold for shielding said separating tubes from direct radiation.

6. A boiler comprising two units each of which comprises an upright tubular downcomer manifold, a series of generating tubes having their lower ends communicating with said downcomer manifold adjacent the lower portion thereof, said tubes being arranged one above another and inclined at an angle to said manifold, an upright tubular intermediate separating manifold communicating with the upper ends of said generating tubes and a series of tubes providing communication between said separator manifold and the upper portion of said downcomer manifold, said units being arranged in two spaced series with the generating tubes of each series extending toward and overlapping the generating tubes of the opposite series, and the adjacent sides of the overlapping generating tubes being provided with chafing ribs for holding the tubes in spaced relation to each other.

Signed at Honolulu this 31st day of January, 1927.
